UNITED STATES PATENT OFFICE

SYLVESTER ELMO SONGEY, OF CHICAGO, ILLINOIS

BOLT

Application filed August 30, 1929. Serial No. 389,470.

This invention aims to provide simple means whereby an upper window sash may be locked to a lower window sash, in adjusted positions, so as to leave a ventilating opening of greater or less size above the upper edge of the upper window.

The device comprises a bolt and a keeper plate wherewith the bolt engages. The invention proposes improvements in the mounting of the bolt and improvements in the keeper plate, the construction being such that the operator does not have to bore a hole for the reception of the end of the bolt unless he wishes to do so.

15 It is within the province of the disclosure to improve generally, and to enhance the utility of, devices of that sort to which the invention appertains.

With the above and other objects in view, 20 which will appear as the description proceeds, the invention resides in the combination and arrangement of parts and in the details of construction hereinafter described and claimed, it being understood that changes 25 may be made in the precise embodiment of the device herein disclosed, within the scope of what is claimed, without departing from the spirit of the invention.

In the accompanying drawings:

25 Figure 1 shows in elevation, portions of a pair of window sashes to which the device forming the subject matter of this application has been applied;

Figure 2 is a section taken through the 30 bolt in a plane close to the face plate that is attached to the bolt casing;

Figure 3 is a longitudinal section showing how the bolt works when no hole is bored in the upper sash for the reception of the 35 end of the bolt;

Figure 4 is a cross section on the line 4—4 of Figure 3;

Figure 5 is a cross section on the line 5—5 of Figure 3;

40 Figure 6 is a perspective view showing one end of the bolt casing.

Figure 7 is a longitudinal section showing how the device looks when a hole is bored in the upper sash to take the inner end of 45 the bolt.

The numeral 1 marks a window frame in which an upper sash 2 and a lower sash 3 are mounted to slide. A keeper plate 4 is attached by securing elements 5 to one stile of the sash 2. The plate 4 has outstanding, 55 longitudinal reinforcing ribs 6. The plate 4 is provided with openings 9, the plate being struck outwardly, as at 7, above the openings, to form shoulders 8; and to form shoulders 28 which slope downwardly and outwardly above the shoulders 8. The reinforcing ribs 6 are located on opposite sides of the shoulders 8.

A tubular casing 10 is mounted in the lower sash 3 and has an opening at its inner end, 60 as Figure 3 will show. At its outer end, the casing 10 has laterally extended flanges 11 which, when the casing 10 is in place, may be countersunk into the lower sash 3, as shown in Figure 7. A face plate 12 abuts 65 against the flanges 11 of the casing 10. The casing 10 is provided at its outer end with fingers 14 located opposite to each other, and 90° remote from the flanges 11. The fingers 14 are received in notches 15 in the 70 edges of the face plate 12, and are held therein by being welded or riveted down. Securing elements 16 hold the face plate 12 against 75 the outer surface of the lower sash 3.

A bolt 17 slides in an opening 21 in the face plate 12, the opening 21 having oppositely-disposed lateral extensions 22, shown best in Figure 2. The bolt 17 is provided with oppositely-disposed projections 18 against which abuts a loose washer 19 on the bolt 17, 80 the washer forming an abutment for a spring 20 that serves to advance the bolt. The spring 20 is a compression spring, located within the casing 10, the outer end of the spring 85 engaging the face plate 12. Near to its outer end, the bolt 17 is provided with oppositely-disposed inner shoulders 23 and with oppositely-disposed outer shoulders 24, the shoulders 23 and 24 being in alignment, lengthwise 90 of the bolt 17, as Figure 7 shows. The shoulders 23 are of such size that they can go through the extensions 22 of the hole 21 in which the bolt 17 slides. There is a head 95 25 on the outer end of the bolt 17, and the 100

bolt has longitudinal grooves 26 that extend within the head.

The bolt 17 may engage the shoulder 8, as shown in Figure 3, and when the bolt is rotated on its axis, the shoulders 23 and 24 are disposed on opposite sides of the face plate 12, thereby to lock the bolt against movement either inwardly or outwardly.

If there is a recess 27 in the upper sash 2, 10 the operator can slide the bolt 17 lengthwise, so that the outer shoulders 24 are within the tubular casing 10, and then, by rotating the bolt so that the outer shoulders 24 are not lined up with the extensions 22 of the 15 opening 21, the bolt will be held advanced, in the position of Figure 7.

By providing both the shoulders 23 and the shoulders 24, the operator may use the seat 27, as in Figure 7, or dispense with it, as 20 in Figure 7, some persons objecting to boring into the sash to form the seat 27.

When it is desired to hold the bolt retracted, the bolt can be rotated until the inner shoulders 23 are lined up with the extensions 25 22 of the opening 21, the bolt being moved outwardly through the extensions 22. Then, if the bolt be rotated through a small arc, the inner shoulders 23 will engage the outer surface of the face plate 12, and hold the bolt 30 retracted.

Having thus described the invention, what is claimed is:

In a sash-holding device of the class described, a tubular casing open at its inner end, 35 a face plate having an opening provided with reduced lateral extensions, a bolt slidable in the opening and of sufficient length to project beyond the inner end of the casing, the bolt being supplied with inner and outer 40 shoulders spaced apart longitudinally of the bolt by a distance approximating the thickness of the face plate, the shoulders being so shaped as to pass through the lateral extensions of the opening when the bolt is moved 45 longitudinally, spring means in the casing for advancing the bolt, the bolt being rotatable to engage the inner and outer shoulders with opposite sides of the plate, thereby to hold the bolt partially advanced, the bolt 50 being rotatable to engage the outer edges of the outer shoulders with the inner surface of the plate when the bolt is fully advanced, thereby to hold the bolt in such position, the bolt being rotatable to engage the inner edges 55 of the inner shoulders with the outer surface of the plate to hold the bolt completely retracted, and means for securing the face plate in place with respect to the casing.

In testimony that I claim the foregoing as 60 my own, I have hereto affixed my signature.

SYLVESTER ELMO SONGEY.
